ELECTRIC BROILER

Maurice David Sado, Lawrence, N. Y.

Application September 24, 1954, Serial No. 32,431

Term of patent 3½ years

(Cl. D81—10)

Fig. 1

Fig. 2

Fig. 1 is a front perspective view of an electric broiler showing my new design.

Fig. 2 is a fragmentary perspective of the broiler as shown in Fig. 1, in open position.

Fig. 3 is a fragmentary side view of the opposite side as that shown in Fig. 1.

The rear view of the electric broiler is substantially plain.

I claim:

The ornamental design for an electric broiler, substantially as shown and described.
